BIT FOR SMOKING PIPES

Wyman Swenson, Lake Mahopac, N. Y.

Application October 28, 1950, Serial No. 192,713

1 Claim. (Cl. 131—229)

This invention relates to smoking devices as smoking pipes and more particularly to the bit for the pipe. In the past smoking pipes have been constructed with a hard smooth bit and in order that the bit may have a sufficient strength to support the pipe and its tobacco in use the bit must be fairly heavy. With most habitual smokers there is a tendency to clamp the heavy bit end between certain teeth as this becomes the most comfortable smoking position for that individual. As a result of the continual clamping action between certain teeth these teeth may be pressed out of their natural position or they may wear out of shape or they may be loosened with respect to the gum thus creating a harmful condition.

An object of this invention is to provide a bit for a smoking pipe that will fit the tooth structure i. e. biting edge of the smoker.

A further object of this invention is to provide a bit having a negative dentiform impression that is tailored to the tooth structure of the smoker.

A still further object of this invention is to provide a smoking bit for a pipe in which the bite area is spread to a plurality of teeth.

A further object of this invention is to provide a bit for a smoking pipe in which the bit is formed with a negative dentiform impression to spread the clamping force over a plurality of teeth.

Other objects of this invention may be apparent by reference to the accompanying detailed description and the drawings in which

Fig. 1 illustrates a perspective view of a pipe,

Fig. 2 illustrates a cross sectional view taken on line 2—2 of Fig. 1,

Fig. 3 illustrates a modified form of bit for a pipe,

Fig. 4 illustrates a top plan view of a cake of wax in which an upper case of a dental impression has been formed,

Fig. 5 is a cross sectional view taken on line 5—5 of Fig. 4,

Fig. 6 is a bottom plan view of the cake of wax with the lower case impression,

Fig. 7 illustrates a perspective view of a further embodiment illustrating a cigarette holder,

Fig. 8 is an enlarged side elevational view of a modified bit end of a smoking device, and Fig. 9 is a plan view taken on line 9—9 of Fig. 8.

Referring to the drawings there is illustrated in Fig. 1 a smoking pipe 10 which is comprised of the usual bowl 11, stem 12 and bit 14. In this particular embodiment of a pipe the components are similar to those found in conventional pipes with the exception of the bit. In this invention the bit is formed or tailored to fit each individual smoker, that is, the pipe bit is constructed with an exterior surface to fit certain teeth according to the desire of the smoker. In the Fig. 1 there is illustrated a plurality of impressions 15 on both the upper and lower surfaces of the bit. Referring to Fig. 2 the impressions in this instance are three in number on both the upper surface and lower surface. It is to be noted that the impressions are not deep, they are only of sufficient depth to permit the teeth to fit firmly into one position so that the bit is maintained in that particular smoking position.

Referring to Fig. 3 there is illustrated a removable bit 14A that is similar in form to the bit 14 of Fig. 1 or the bit illustrated in Fig. 7 except that bit 14A is removable from the stem 12A of the pipe. The bit may be secured

2

in any of the conventional pipes but in this instance we have illustrated the bit as having a threaded socket 16 that may be easily threaded to and affixed about the threaded stem 12A. In addition in this embodiment there are illustrated a plurality of smoke ports 22 formed in the bit and connected at their opposite ends to the central bore 23 of the pipe stem 12A.

Referring to Figs. 4, 5, and 6 there is illustrated a cake of wax 20. The cake 20 is utilized to form a negative impression of the smoker's bite. Fig. 4 illustrates the impression of the upper case while Fig. 6 illustrates the impression of the lower case and Fig. 5 is a cross sectional view illustrating the impressions formed by both the upper and lower cases. With the cake 20, a plaster mold may be formed to copy the dentiform impression of the smoker and in particular the bite area. Although the bit illustrates the three impressions, whereas the cast may illustrate more than three, it is apparent that the width of the bit limits the impressions to three while the cast is preferably made wider to assure the mold maker of a good clean, clear impression to use in making the bit. With the plaster cast the bit 14 may then be formed as illustrated in Fig. 1. The manner of formation of the bit varies, that is, it may be cut or drilled to the configuration illustrated or it may be poured of a material that will harden and set according to the impression, but the method of formation is not a part of this invention, rather it is the article formed from the smoker's bite as illustrated in Figs. 1, 2 and 3.

Referring to Fig. 7 there is illustrated a cigarette holder 30, which is nothing more than a bit similar to that illustrated in Fig. 1 with the same tailored biting edges in which there are a plurality of impressions 15 on both the upper and lower surfaces of the bit and in which the stem 31 at the opposite end to the bit is provided with a hollow barrel formation 32 into which a cigarette may be inserted and retained for smoking. The hollow barrel 32 is in turn connected to a central bore or smoke aperture 33, the bore 33 in turn being connected to the central smoking bore 34 in the bit end of the cigarette holder 30. The cigarette holder 30 is similar in formation, that is, on the bit end and is retained by the smoker in a firm grip without harm to the teeth due to the tailored bite formation. The cigarette holder 30 is constructed in the same manner as that already disclosed for the pipe 10.

Although we have illustrated in Fig. 1 a bit with a single row of upper case and a single row of lower case impressions there are some smokers who retain their pipe on one side of their mouth and for relaxation move the pipe to the opposite side of the mouth. Thus it becomes necessary in such instance to provide two cakes 20 marked with a right side bite and a left side bite. Thus the mold maker will in this instance form the bit 14 with two rows of impressions on each of the upper and lower surfaces of the bit. The finished pipe will then be similar to that illustrated except for an additional row of impressions on each surface of the bit. The smoker is then provided with a pipe that may be clamped equally well in either the left or right bite positions. Referring to Figs. 8 and 9 it is apparent that the smoker may readily clamp the bit of the pipe in the right side of his mouth by fitting the proper teeth into the impressions formed on the line B—B of Fig. 9 and the smoker may similarly place the bit of the pipe into the left side of the mouth and in this instance the teeth should find the proper impressions formed on the line A—A of Fig. 9.

A further feature of the bit of this invention is the fact that it is widened at the end to provide a wider area of bite and in turn the hollow center smoke bore 21 may be spread over a greater area thus permitting a greater area of cooling for the smoke and this will tend to provide a cooler smoke for the smoker.

Various changes or modifications may be made to the smoking bit for a pipe such as the manner of affixing the bit to the stem of the pipe or as to the composition of which the bit may be constructed or as to the number of impressions formed in the bit according to the number of teeth usually used to form a proper bite without

departing from the spirit of this invention and this invention shall be limited only by the appended claim.

What is claimed is:

A removable bit provided in one end of a tubular element such as the stem of a pipe, said bit provided with a plurality of rows of tooth impressions on each of the upper and lower surfaces, a row of impressions of the upper surface matching with a corresponding row of impressions of the lower surface to fit the bite of the smoker, said rows of matching impressions on opposite surfaces being in approximately parallel relationship, said matching impressions tailored to fit the left and right bite of the smoker. 10
